1052.

To all whom it may concern:

Be it known that I, Gustav Heidrich, a citizen of the United States, residing at Detroit, in the county of Wayne and State of Michigan, have invented a new, original, and ornamental Design for an Ash Tray or Similar Article, of which the following is a specification, reference being had to the accompanying drawing, forming part thereof.

Figure 1 is a top plan view of an ash tray or similar article showing my new design.

Figure 2 is a side elevation of the ash tray or similar article.

Figure 3 is a front elevation of the ash tray or similar article.

I claim:

The ornamental design for an ash tray or similar article, as shown.

GUSTAV HEIDRICH.
